HOSE NOZZLE

Robert A. Gilmour, ½ Gilmour Manufacturing Co.,
Somerset, Pa.

Filed Nov. 20, 1961, Ser. No. 67,609

Term of patent 14 years

(Cl. D91—1)

FIGURE 1 is a side elevational view of a hose nozzle embodying my new design;

FIGURE 2 is a front elevational view of a nozzle; and
FIGURE 3 is a top plan view of the nozzle.

The dominant features of my new design are shown in solid lines.

The side not shown is substantially the same in appearance as the side shown and the rear of the vertical member is substantially the same as the front except for the projecting stud.

I claim:
The ornamental design for a hose nozzle, as shown.
